CLIMBER

Robert L. Woodbury, Litchfield, Conn.

Application March 27, 1944, Serial No. 528,260

4 Claims. (Cl. 227—27)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

This invention relates to climbers, and more particularly to an improved climbing iron for use by members of the armed forces, linesmen and other persons in ascending or descending trees, poles and the like.

It is essential that the weight and bulk of equipment for members of the armed forces be restricted to a minimum consistent with safety and efficiency. This is especially true in the equipment for members of groups that operate in jungles or other remote locations. In jungle warfare, or in establishing remote communication systems, climbing irons or spurs are frequently required to climb trees, poles and the like. Linesmen who are required to remain supported in an elevated position by climbing irons for relatively long periods of time, usually prefer heavy irons which have heavy shanks extending a considerable distance up the leg. Each shank is secured to the leg by a heavy strap and, usually, a thick pad is interposed between the shank and the trouser leg to protect the leg against injury from the shank of the iron. Under conditions in which the greater portion of a linesman's or mechanic's time is spent on the ground, and only relatively short periods of time are utilized in climbing, the conventional heavy climbing irons or spurs are not required, but, on the contrary, small or light irons are greatly preferred.

An object of this invention is to provide a climbing iron which is relatively small and of little weight, but one which is strong and durable and which may be conveniently secured to the foot and leg of the user.

Another object of this invention is to provide a relatively strong and light climbing iron which is constructed and arranged to distribute the stresses resulting from the imposition of the user's weight upon the iron, so that no discomfort is caused by its use in ascending or descending trees, poles and the like.

A further object of this invention is to provide a climbing iron having a foot support, a shank, straps for securing the foot support and shank to the foot and leg of the user, and a tapered spur extending downwardly and forwardly from the foot support, the axis or intermediate portion of the spur lying in a plane that passes through the point at which the shank is secured to the leg strap.

A specific object of this invention is to provide a climbing iron having a foot support or tread

for engaging the sole of the instep of the shoe of the user, a shank extending rearwardly and upwardly from the outside terminal of the tread, and a spur or gaff extending downwardly from the opposed or inside terminal of the tread, and means for securing the climbing iron to the foot and leg of the user.

A more specific object of this invention is to provide a climbing iron having a foot support or tread for engaging the sole of the instep of the shoe of the user and having eyes formed therein, a shank extending rearwardly and upwardly from a terminal of the tread, a spur extending downwardly from the opposed terminal of the tread, a loop on the shank, a strap adapted to pass through the eyes of the tread and engage the shoe of the user to secure the tread to the instep portion of the shoe, and a strap adapted to pass through the loop on the shank and engage the leg or leg covering of the user to secure the shank to the leg, the strap resisting the stress imposed on the shank by the weight of the user resting on the tread while the spur is supported against downward movement.

It is also an object of this invention to provide a climber of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts and details of construction hereinafter described and claimed, it being understood that various changes in form, proportion and minor details of construction may be made within the scope of the claims without departing from the spirit or sacrificing any advantages of the invention.

For a complete disclosure of the invention, a detailed description thereof will now be given in connection with the accompanying drawing forming a part of the specification, wherein:

Fig. 1 is a side elevation of the improved right climbing iron;

Fig. 2 is a front view thereof, parts appearing in sections;

Fig. 3 is a side elevation, looking in the opposite direction from Fig. 1;

Fig. 4 is a plan view;

Fig. 5 is a transverse sectional view taken on a line 5—5 of Fig. 1; and

Fig. 6 is a perspective view depicting the application of a right climbing iron and a left climbing iron to the feet and legs of the user.

Referring to the drawing, in which correspond-

ing parts are indicated by similar reference characters, there is depicted a climbing iron or spur 10 which includes a curved or arcuate foot support or tread 11 formed of relatively thick material, and a portion of the tread is cut away to provide material for a spur or gaff 12. The spur 12 extends downwardly and slightly outwardly relative to the tread 11, as best seen in Fig. 2, and it is preferably V-shaped, as best seen in Figs. 1 and 3, with a piercing point 15 formed at its lower terminal. A sharp edge 16 is formed along the forward portion of the spur 12, and this edge is disposed perpendicular to the tread 11. The rear edge of the spur 12 is also sharpened, as indicated at 17, and this edge is preferably disposed at an angle to the tread 11, thereby causing the spur to tilt forwardly, for reasons to be hereinafter explained.

The inner terminal of the tread 11 is upwardly and outwardly turned, as indicated, to provide a holding flange 18, and this flange has a strap-receiving eye 20 formed therein. By this arrangement, the spur 12 and upwardly turned flange 18 are located at one terminal of the tread 11, and the opposed terminal of the tread is welded or otherwise secured to the lower terminal of a strip of thinner material, which forms the shank 22 of the climber. By this arrangement, the terminal of the tread 11 which is remote from the spur 12 is thickened or reinforced, as indicated at 21, and the shank 22 then extends rearwardly and upwardly from the tread 11, and has a loop 23 formed adjacent its upper terminal. This loop is preferably formed by stamping it outwardly from the upper terminal of the shank 22, as best seen in Figs. 1, 2, and 3, although it is to be understood that the loop may be otherwise formed. The portion of the shank 22 which lies between the tread 11 and the loop 23 is preferably outwardly bowed, as indicated at 25, and the upper terminal of the shank 22 is turned outwardly, as indicated at 26.

A strap-receiving recess or eye 27 is formed in the lower portion of the shank 22 adjacent its forward edge, and this eye is preferably arranged opposite the eye 20 formed in the upwardly turned flange 18 of the tread 11.

A securing strap 30 extends through the opposed eyes 20 and 27, and the terminals of this strap are secured together by a buckle 31, as best seen in Figs. 2 and 6. Another securing strap 32 passes through the loop 23 formed adjacent the upper terminal of the shank 22, and the terminals of this strap are preferably secured together by a buckle 33, which is best seen in Fig. 5.

The climbing irons 10 are provided in pairs, each pair including a right iron and a left iron. In use the tread 11 of a climbing iron is passed under the instep portion of the shoe of the user in engagement with the sole, and then the instep strap 30 is tightened and finally secured by the buckle 31. Inasmuch as the lower portion of the shank 22 of each climbing iron 10 is offset forwardly, the upper portion 22 of the shank is disposed substantially in alignment with the leg of the user, and the strap receiving loop 23 is positioned adjacent the user's ankle. The shank 22 of the iron 10 is secured to the user's ankle, or ankle covering, by means of the strap 32, and the buckle 33.

When the right and left climbing irons 10 are secured in place on the user's feet, the shanks 22 are disposed at the outer sides of the feet and the spurs 12 are located at their inner sides, as best seen in Fig. 5. Inasmuch as the spur 12 in each climber 10 is located at one side of the foot,

and the shank 22 at the opposite side, and since the upper terminal of the shank 22 is secured to the ankle by the strap 32, it is manifest that the stresses imparted to the shank 22 by the engagement of the spur 12 with the tree, pole or other support, and with the weight of the user resting on the tread 11, the shank 22 tends to move outwardly away from the user's foot and leg, but this tendency of the shank 22 to move outwardly is resisted by the strap 32. Inasmuch as the strap 32 extends around the ankle of the user, it is obvious that the stresses imparted to the strap through the shank 22 are distributed around the inner portion of the user's ankle, thereby preventing excessive stress being applied to a small portion of the ankle. In this arrangement, the shank tends, as stated, to move outwardly away from the user's ankle or leg, and since the intermediate portion of the shank 22 is outwardly bowed, as indicated at 25, no portion of the shank engages the user's shoe or leg under excessive stress during the climbing operation.

During the climbing operation the user's weight is supported by the tread 11 and spur 12 which are formed of relatively thick material to safely carry the load. Inasmuch as the supporting spur 12 is located at the inner side of the foot, the user's weight tends to throw the shank 22 outwardly away from the foot and ankle, but the outward movement of the shank is restricted by the strap 32. This tends to bend or break the climber iron 10 at the junction between the tread 11 and shank 22, but since this portion of the device is reinforced or thickened, it is manifest that this tendency is restricted by the reinforcement 21.

In climbing trees, poles and the like, the person climbing usually kicks downwardly and forwardly, and inasmuch as the V-shaped spur 12 extends forwardly, it offers less resistance in entering the tree or support. The shank 22 is located somewhat behind the tread 11, and since the downwardly-tapered spur 17 is inclined forwardly, its axis or intermediate portion lies in a plane that passes through the point at which the strap 32 engages the loop 23 of the shank 22, as indicated by the dotted line 35 in Figure 3, so that some of the thrust is resisted by the strap 32 without moving the shank relative to the strap. The outer edges 16 and 17 of the spur are sharpened to taper outwardly, and the lower sharpened terminal 15 is also tapered.

From the foregoing, it will be seen that applicant has provided a relatively light and small climbing iron which is easily and conveniently secured to the shoe and ankle of the user, and which is constructed and arranged to provide maximum safety in climbing. It also protects the user against discomfort or injury by its use, inasmuch as its shank tends to move away from the user's foot and ankle when the weight of the user is supported on the spur 12 and tread 11. The improved climbing iron is of minimum weight, because the stress receiving portions are formed of relatively heavy or thick material, and the shank or retaining portion is formed of relatively thin or light material.

Having thus described my invention, what I claim as new and useful is:

70 1. A climber including a tread adapted to engage the instep portion of the shoe sole of the user, a shank extending upwardly from one terminal of the tread at the outer side of the shoe and bowed outwardly away from the shoe, the upper terminal of the shank being outwardly

turned, a spur extending downwardly from the opposed terminal of the tread at the inner side of the shoe, means for securing the tread to the shoe, and means for securing the upper portion of the shank to the leg of the user.

2. A climber including a tread adapted to engage the instep portion of the shoe sole of the user, a shank extending upwardly from one terminal of the tread at the outer side of the shoe, a tapered spur extending downwardly and forwardly from the opposed terminal of the tread at the inner side of the shoe, means for securing the tread to the shoe, and means for securing the shank to the leg of the user.

3. A climber including a tread adapted to engage the instep portion of the shoe sole of the user, a shank extending upwardly from one terminal of the tread at the outer side of the shoe, a tapered spur extending downwardly and forwardly from the opposed terminal of the tread at the inner side of the shoe, means for securing the tread to the shoe, and means for securing

the shank to the leg of the user, the axis or intermediate portion of the spur being located in a plane that passes through the point at which the shank is secured to the leg of the user so that the thrust of the spur is resisted by the said leg securing means.

4. A climber including a tread adapted to engage the instep portion of the shoe sole of the user, a shank extending upwardly and rearwardly from one terminal of the tread at the outer side of the shoe, a tapered spur extending downwardly and forwardly from the opposed terminal of the tread at the inner side of the shoe, means for securing the tread to the shoe, and means for securing the shank to the leg of the user, the axis or intermediate portion of the spur being located in a plane that passes through the point at which the shank is secured to the leg of the user so that the thrust of the spur is resisted by the said leg securing means.

ROBERT L. WOODBURY.
